STRIKING AND CHIME CLOCK

Arthur B. Campbell, Thomaston, Conn., assignor
to Seth Thomas Clock Company, Thomaston,
Conn., a corporation of Connecticut

Application December 7, 1932, Serial No. 646,131

4 Claims. (Cl. 58—13)

My invention relates to striking and chime clocks and has for its object the production of such a clock in which the rate of striking either the hour striking or chime striking can be definitely regulated in an extremely simple, inexpensive and effective manner and at the same time eliminate the noises that were given out by these devices which were used previous to my invention.

5 A further object of my invention is the production of mechanism associated with the gathering cam, the rack and the snail of such clocks to eliminate the noisy operation previously usual in such clocks.

10 A further object is the production of a demountable bushing which has for its object the direct connection of the current leads with the clock movement on the back plate, eliminating all the present inside wiring and eliminating also the terminal block that was formerly used on the case 15 itself, and still provides a detachable cord which is very much desired by such clock users.

15 I accomplish these objects by the means shown in the accompanying drawings in which:

Fig. 1 is a front view of the clock movement.
20 Fig. 2 is a partial front view of the clock movement showing the quarter-hourly chime mechanism.

Fig. 3 is a right side view of the Figure 2.
25 Fig. 4 is a partial front view of the clock movement showing the hour-strike mechanism.

Fig. 5 is a left side view of Figure 4.
30 Fig. 6 is a partial top view of the clock movement showing the magnetic speed control device.

Fig. 7 is a front view of Figure 6.

35 Fig. 8 is a right side view of Figure 7.

Fig. 9 is a partial rear view of the clock case showing the demountable cord bushing.

Fig. 10 is a sectional view along a line 1—1 of Figure 9.

40 Similar numerals represent the same parts throughout the several views.

In the drawings 1 represents the front plate and 2 the rear plate of the clock. A synchronous electric motor is mounted between plates 1 and 2 and is indicated by rotor shaft 3 on which shaft is mounted the rotor pinion 4. The power of said motor is transmitted by means of pinion 4 and the usual train of gears (shown in Fig. 1) to the center shaft 5 to which the minute hand (not shown) is attached.

Said center shaft 5 is journally mounted in plates 1 and 2. The gear 6 is mounted on shaft 5 and engages the teeth of gear 7 on the right side and also the teeth of gear 8 on the left side 55 thereof.

Gear 7 is frictionally mounted on shaft 9 which is journalled in plates 1 and 2 and which shaft 9 serves as the arbor for a spring (not shown) coiled in spring barrel 10 which spring is thus wound through the gear train by the electric motor and stores up the power to operate the quarter-hourly chime mechanism. Integral with spring barrel 10 is the gear 11 which engages the teeth of gear 12 mounted on shaft 13. Shaft 13 carries the gear 14 meshing with pinion 15. Said pinion 15 is mounted on shaft 16 journalled between plates 1 and 2. The shaft 16 carries the gear 17 which gear 17 has the stop pin 18 mounted on its rim, as shown. The gear 17 engages pinion 19 mounted on shaft 20 which shaft 20 is journalled between 15 and in plates 1 and 2. The shaft 20 carries the gear 21 which gear has mounted on its rim the stop pin 22, as shown. Shaft 13 also has mounted on its front end the chime cam 23 which has notches 24 cut in its periphery and which cam carries the pin 25 as shown.

Integral with chime cam 23 is auxiliary chime cam 26 which has a notch 27 cut in its periphery (see Fig. 3). Engaging said cam 23 is the lever 28 mounted on shaft 29 which is journalled in 25 the plates 1 and 2. Said lever 28 has a projection 30 which engages the notches 24 of cam 23. Said lever 28 has a further projecting element 31 the end 32 of which engages the stop pin 22 on gear wheel 21.

Said shaft 29 carries the forked lever 33 comprising member 34 and member 35. The right angled projection 36 at the end of member 34 engages the stop pin 22 on gear wheel 21. A further right angled projection 37 at the end of member 35 of said forked lever 33 engages the quatrefoil cam 38 which is mounted on the center shaft 5.

At the end of shaft 13 adjacent to rear plate 2 (see Fig. 3) is mounted the gear 39 which meshes with the gear 40 which is journally mounted on the projecting end of shaft 9 which gear 40 engages the gear 41 fastened on camshaft 42 which camshaft carries the chime cams 43 and is journalled between rear plate 2 and auxiliary plate 44. 45

Said chime cams 43 are locked together as a unit to give the desired chime sequence and have on their periphery the teeth 45 which engage the projections 46 on the levers 47 which levers 47 are independently and rotatably mounted on the shaft 48 which is journalled in the plates 2 and 44. Said levers 47 carry the strike rods 49 at the end of each of which is adjustably attached the usual strike hammer 50 (see Fig. 1) which strikes the usual gong rod 51 as shown. 55

The auxiliary locking system comprising levers 52 and 53 mounted on the shaft 54 journaled in plates 1 and 2 is shown in (Figs. 1 and 3). Lever 52 has a follower point 55 which engages the notch 27 of auxiliary chime cam 26 and the lower edge of said lever 52 rests on a pin 57 carried by lever 28. The lever 53 has a projection 56 which engages the pin 18 on gear wheel 17. The gear 8 is frictionally mounted on shaft 58 which 10 is journaled in plates 1 and 2, and said shaft 58 serves as the arbor for a spring (not shown) coiled in spring barrel 59 which spring is thus wound through the gear train by the electric motor and stores up the power to operate the 15 hour strike mechanism. Formed on spring barrel 59 is the gear 60 which engages the teeth of pinion 61 mounted on shaft 62 which carries the gear 63 which meshes with pinion 64 which is mounted on shaft 65 journaled in plates 1 and 20 2. The shaft 65 carries the gear 66 which engages pinion 67 mounted on shaft 68 which shaft is journaled in plates 1 and 2 and carries the gear 69 which gear has mounted on its rim the stop pin 70 as shown. The shaft 65 has mounted 25 on its front end in front of plate 1 (shown in Fig. 4) the oval cam 71 which carries a pin 72. Engaging said cam 71 is the lever 73 journaled on the stud 74 which is fastened in plate 1. Said lever 73 has the right angled projection 75 which 30 engages the periphery of the cam 71 and further has a pin 76 mounted adjacent to its right hand end as well as a projection 77 which extends through an aperture in the plate 1 and which engages the stop pin 70 on gear wheel 69. The 35 projection 75 on lever 73 rides on the surface of the oval cam 71 so that the pin 76 will be gently lowered into engagement with the rack so as to avoid any clicking sound such as would occur if it were dropped suddenly against the teeth of the said rack.

40. the said rack. Journalled on a stud 78 which is fastened on plate 1 is the rack member 79 which has the proper number of teeth 80 which teeth are always so positioned that they will be engaged by the pin 72 on oval cam 71 when said cam is rotated. Attached to the end of rack member 79 is the buffer spring 81 as shown. Integral with rack member 79 is the stop finger 82, which engages with the step of the snail 83 which has twelve such steps or segments of decreasing radii corresponding to the twelve periods that the hour-strike mechanism shall function. Said snail 83 is journalled on the center shaft with the usual hour hand mechanism (not shown) of the clock and is operated as a part of the usual dial train of the clock (not shown).

Journalled on stud 84 mounted on plate 1 is the hour trip lever 85 whose end 86 is so disposed as to lie in the path of the pin 25 on chime cam 23. Integral with trip lever 85 is the stop lever 87 which has a projection 88 which extends through an aperture in the plate 1 and engages stop pin 70 on gear wheel 69. Said lever 87 carries a pin 89 which engages the lower edge of lever 73 as shown (Fig. 4).

Mounted on shaft 62 is the star wheel 90 comprising a plurality of teeth 91 which teeth engage the projection 92 of the arm 94 of bell crank lever hub 93 which also has another arm 95 as shown. Said lever hub 93 being journalled on stud 96 fastened in the plate 2. Said projection 92 of arm 94 extends through an aperture in plate 2 as shown. The arm 95 of lever hub 93 has a suitably formed end 97 which engages a pin 98 mounted in lever 99 which is attached to the

bushing 100 which also has a lever 101 fastened thereto. Said levers 99 and 101 by means of bushing 100 are journaled on the shaft 48 which carries the levers 47 of the chime mechanism previously described. Said lever 101 carries the hour strike rod 102. Hour strike rod 102 carries a strike hammer (not shown in Fig. 4) which strikes the hour gong rod as previously described. 5

Journally mounted in plates 1 and 2 (see Figs. 1 and 6) is the shaft 103 carrying the pinion 108 which engages the teeth of gear wheel 69. Mounted on shaft 103 is a metallic disk 104 which may be made a highly current conducting metal such as copper or aluminum or of a conducting metal which is highly magnetic such as iron or iron alloys. Adjacent to said disk 104 is the permanent magnet 105 which is located on the inner side of plate 2 by means of the pin 106 and clamped in position by means of the thumb nut 107 and curved slot 108 in plate 2 thereof. The magnet 105 is of the horse shoe type and having its opening 109 by means of which the pole pieces may be made to encompass more or less of the disk 104 by swiveling said magnet 105 about the pin 106 using the thumb nut 107 and slot 108 above described.

The above described magnetic device is utilized to control the speed of the hour strike mechanism. A similar magnetic speed control device for the chime mechanism engages the gear wheel 30 by means of a pinion 118A mounted on the shaft 103A as shown in Figs. 6 and 7.

A demountable bushing for the cord connecting the clock to the power supply is shown in Figs. 9 and 10 in which 110 represents the back of the clock casing and 111 the door. Line 112 is the edge of the door opening into which the recess 113 is cut. Said recess 113 is semi-circular at its inner extremity and positions the spring clip or holder 114 which is secured to the casing by means of the nail 115 as shown. Bushing 116 is held by spring clip 114 but can be pressed in or out along the line 1-1 (Fig. 9) as desired. The lug 117 on bushing 116 fits into the recess 113 and prevents the turning of said bushing. It is evident that by means of this demountable bushing device that the clock movement can always be removed from the casing without in any way disconnecting the conducting wires from the clock movement.

In operation my clock is driven by a synchronous electric motor, the power being transmitted through the indicated train of gears of proper ratio to the center shaft 5 from which the usual minute and hour hands are driven. The gear wheel 6 on the center shaft 5 meshes with gear wheel 1 to wind the spring which powers the chime strike mechanism and with gear wheel 8 to wind the hour strike spring. Both gear wheels 1 and 8 are frictionally mounted to prevent overwinding and consequent breaking of the springs. The quatrefoil cam 38 on center shaft 5 being mounted and synchronized with the minute hand, raises and drops the projection 31 of lever 33 every quarter hour, thus putting the chime strike mechanism into operation every quarter hour. When the lever 33 nears the point of maximum rise on cam 38 the projection 32 of lever 28 is drawn from the circular path of pin 22 on gear wheel 21 and said gear wheel 21 being under pressure from the chime strike spring in spring barrel 10 is free to rotate. The raising of lever 33, however, also raises member 34 of lever 33 whose projecting end 36 is interposed in the circular path 75

of pin 22 on gear wheel 21 thus locking the system after the gears have made only a fraction of a turn. This fraction of a turn gives the chime cam 23 sufficient rotation so that projection 30 of lever 28 cannot again enter the notch 24 in cam 23 from which it was raised, forcing projection 30 to ride on the periphery of cam 23 and keeping projection 30 of lever 28 out of the circular path of pin 22 on gear wheel 21.

When the projection 37 of lever 33 subsequently drops off the high point of lobe cam 38 the projection 36 of lever 33 drops from the circular path of pin 22 on gear wheel 21 thus freeing the chime gear train. The gear 39 on shaft 13 now being in rotation drives the cam shaft 42 through gears 40 and 41 and the cams 43 on camshaft 42 rotate, causing the teeth 45 to actuate the levers 47 and at the same time the strike rods 49 and hammers 50. The proper amount of rotation of the cam 23 (as required by quarter-hour chime, half-hour chime, etc.) is governed by the amount of circumferential distance between notches 24 on cam 23, for it is evident that when the next succeeding notch 24 is reached by the projection 30 on lever 28, said projection 30 will enter said notch, again interposing projection 32 of lever 28 in the circular path of pin 22 on gear wheel 21 thus locking the system until the next lobe of the quatrefoil cam 38 is rotated to repeat the above sequence, a quarter of an hour later until the three quarter chime has been sounded.

After the three quarter hour chime has thus been sounded the cam 26 which has the single notch 27 still has the point 55 riding on the dwell or outer part of the cam 26 which holds lever 52 and 53 in the upper or raised position in which the stop 56 is withheld from the path of the pin 18 on the relatively high speed gear 17 so that to release the chime strike for the first three quarters of the hour it is only necessary to lift the levers 28 and 32 the normal distance by means of each of the three equal lobes of cam 38. At the end of the third quarter chimes the chiming as above mentioned is stopped by stop 32 engaging pin 22 in the usual manner. At the same time the point 55 drops into the said notch 27 in cam 26 which brings the stop 56 into the path of the pin 18. As the minute hand completes the hourly period the fourth lobe of the cam 38 which, as is usual in all chime synchronizing devices which are already old in the art, is longer than the other three lobes, acts in the manner of the shorter lobes to remove the stop 32 from the path of the pin 22 but raises lever 28 higher than do the other three lobes causing the pin 57 to engage lever 52 and raise it sufficiently to remove the stop 56 from the path of pin 18 through the intermediary of lever 53 to release the chimes to strike the hour. Thus, by virtue of the fact that on the hour it is necessary for the long lobe on cam 38 to release fourth quarter chime the fourth quarter chimes will only strike on the even hour, so that if for any reason the clock mechanism will be in condition to chime the hour when it should chime the half or three quarter hour, the chime will remain silent until the minute hand comes into synchronization with the chimes at which time the long lobe of cam 38 releases the chime to strike the fourth quarter chimes.

The hour strike mechanism is put into operation by the raising of the trip lever 85 by means of its slantly shaped end 86 engaging the pin 25

on chime cam 23. Said pin 25 being so disposed on chime cam 23 that said trip lever 85 will be raised immediately after the hour chime strike has functioned, as above described.

When trip lever 85 is raised as above mentioned its associated stop lever 87 rotates in counter-clockwise direction, causing pin 89 in said lever 87 to raise lever 73 which raising of lever 73 takes projection 77 out of the circular path of stop pin 78 on gear wheel 69 and temporarily frees the hour-strike gear system. The gear wheel 69 may then make a fraction of a revolution, i. e., until pin 70 on gear wheel 69 is stopped by projection 88 of lever 87 which has been interposed in the circular path of pin 70 by the counter-clockwise movement of lever 87. The gear system is thus held locked until the end 86 of trip lever 85 drops off the pin 25 on chime cam 23 at which time projection 88 of lever 87 is withdrawn from the pin 70 on gear wheel 69, permitting the gear system to operate the hour-strike system. The projection 77 on lever 73, however, cannot at this point drop far enough to stop the pin 70 on gear wheel 69 because with the raising of lever 73, the pin 76 on said lever 73 no longer restrains the rack member 79 which rack under the influence of the spring tension shown rotates in a counter-clockwise direction so that the pin 76 on lever 73 falls on the teeth 80 of rack member 79 when said lever 73 is permitted to thus rotate. Said lever 73 is held sufficiently raised by said teeth 80 to keep projection 77 on lever 73 out of the path of pin 70 on gear 69. Rock member 79 thus rotates in a counter-clockwise direction until its stop finger 82 comes into contact with one of the surfaces of the snail 83. It is evident that the number of teeth 80 on rack member 79 which are permitted to pass to the left of pin 76 on lever 73 is determined by the angular position of snail 83 which snail 83 is synchronized or rotates with the hour hand of the clock. The rotation or fall of said rack member 79 in counter-clockwise direction is silenced by the buffer spring 81 acting against the center hub of chime cam 23 making its operation practically noiseless.

With the required number of teeth 80 on rack member 79 to the left of pin 76 on lever 73 and the gear train in motion, the oval cam 71 rotates in a counter-clockwise direction and pin 72 on said cam 71 engages the spaces between the teeth 80 and ratchets said rack member 79 to the right, one tooth at a time with each rotation of said cam. Said pin 76 on lever 73 is correspondingly raised and drops into the next tooth space one space at a time. This continues until pin 72 on cam 71 has gathered all the remaining teeth and the pin 76 on lever 73 drops over the left hand edge of rack member 79, which drop interposed projection 77 of lever 73 in the circular path of stop pin 70 on gear wheel 69 thus locking the gear system. The pin 76 having dropped with lever 73, serves to hold rack member 79 to the right, in position to repeat the above described cycle one hour later. It will be seen that the number of teeth 80 on rack member 79 to be gathered by pin 72 on cam 71 at any given hour will correspond to the number of strokes to be struck by the hour strike mechanism and that each revolution of the cam 71 will produce a stroke of the strike mechanism.

The teeth 91 of star wheel 90, being of such pitch that one tooth 91 is indexed for each revolution. 75

lution of the cam 71, and engaging the projection 92 of member 94 of bell crank lever 93 will give said lever 93 a reciprocating motion about the stud 96. Said reciprocating motion is further transmitted through bushing 100 and lever 101 to the strike rod 102 causing the hammer attached thereto to strike the gong rod as previously described.

The adjustable magnetic speed control or 10 brake, enables the clock user to regulate the speed of both the chime strikes and hour strikes. The manual adjustment is effected by loosening the thumb-nut 107 (Figs. 6, 7 and 8) and shifting said thumb-nut 107 to the right or left in 15 the curved slot 108. Said shift or thumb-nut 107 causes the magnet 105 to swivel about the pin 106 and to intercept more or less of the disk 104, maximum braking action being secured when all the lines of force of said magnet 105 20 act upon said disk 104.

It will be understood, of course, that while I have here shown one form of my device I do not wish to limit it to the exact construction shown but desire to have it taken in a sense illustrative 25 of any or all the forms that come fairly within the scope of the appended claims.

I claim:

1. In a clock, a striking mechanism comprising a rack, rotating parts and a snail and means 30 associated with said rack restraining it from freely dropping to strike said snail, said means

comprising a resilient member mounted on said rack in frictional engagement with one of said rotating parts.

2. In a clock, a striking mechanism comprising a rack, a snail and a resilient member mounted on said rack and means on said frame contacted by said resilient member thereby restraining it from freely dropping to strike said snail.

3. In an electric clock, a casing having an 10 aperture, a door closing said aperture, an electric motor and a time indicating means actuated thereby mounted in said casing, conducting wires connected to said motor extending beyond said casing, means removably connecting said conducting wires with said casing comprising a notch 15 cut into the edge of said aperture and a member having an aperture through which said conducting wires pass removably mounted in said notch, said member having means thereon whereby said member is secured in said notch when the door 20 is closed.

4. In an electric clock, a casing with an aperture, a door mounted to close said aperture, said aperture having a notch in the wall thereof and a member having an aperture with means thereon whereby said member registers with said notch and is removably mounted therein and locked therein when said door closes said aperture.

ARTHUR B. CAMPBELL.

30
